(57) **CLAIM**

The ornamental design for a screw thread repair kit, as shown and described.

DESCRIPTION

FIG. 1 is a perspective view of an embodiment of the screw thread repair kit;

FIG. 2 is a top plan view of the embodiment of FIG. 1;

FIG. 3 is a bottom plan view of the embodiment of FIG. 1;

FIG. 4 is a left elevation view of the embodiment of FIG. 1;

FIG. 5 is a right elevation view of the embodiment of FIG. 1;

FIG. 6 is a front elevation view of the embodiment of FIG. 1; and,

FIG. 7 is a rear elevation view of the embodiment of FIG. 1.

The broken lines, and the unshaded areas within, illustrate portions of the screw thread repair kit and form no part of the claimed design.
